UNITED STATES PATENT OFFICE.

HERMAN C. PRIEBE, OF BLUE ISLAND, ILLINOIS.

CAR DOOR.

Application filed January 29, 1921. Serial No. 440,988.

To all whom it may concern:

Be it known that I, HERMAN C. PRIEBE, citizen of the United States, residing at Blue Island, in the county of Cook and 5 State of Illinois, have invented a certain new and useful Improvement in Car Doors, of which the following is a full, clear, concise, and exact description.

My invention relates to doors which are 10 bodily movable in their own planes, such as are employed, for example, in the sides of freight cars. In practicing my invention I employ mechanism for forcing the bodily movement of a door in its own plane comprising one element in the form of a block and another element in the form of a lever 15 engaging the block, one of these elements being carried by the door and the other being mounted apart from the door upon one side 20 thereof.

In accordance with one feature of my invention the block is formed with a channel that receives the lever and is so shaped and disposed to contain the lever in the various 25 positions to which the lever is swung in moving the door and to have one side engaged by the lever when the lever is moved in a door opening direction and the opposite side engaged by the lever when the lever is 30 moved in a door closing direction.

In accordance with another characteristic 35 of the invention the block is formed partially to overhang the lever when the door is in a closed position to enable the lever and the block to take part in holding the door closed. Where the block is formed with the 40 described channel the overhanging formation of the block keeps the lever within the channel until the door has been sufficiently opened to permit the lever to pass by the overhanging formation.

In the preferred embodiment of the invention the channel in the block is oblique and is margined at each side by an overhanging portion, both overhanging portions 45 serving to maintain the lever and block in assembly when the door is closed and until the door is sufficiently open to permit movement of the lever between the overhanging 50 portions, which overhanging portions have opposing edges that are obliquely arranged and spaced apart sufficiently to permit the lever to be moved through the space between these opposing edges when the lever has been 55 sufficiently swung in a door opening direction to bring it into alignment or registry

with the space between said opposing oblique edges of said overhanging portions.

In accordance with another characteristic 60 of the invention I swingly mount the block upon the door so that it may be turned to serve as a handle by which the door may also be moved, this feature of the invention 65 making it unnecessary to employ a special handle to continue the movement of the door in the portion of its travel where the lever could not have door moving engagement 70 with the block.

My invention may be employed in connection with a single door or a double door, 70 the accompanying drawings showing both of these embodiments of the invention. In the drawings Fig. 1 illustrates a portion of a freight car in side elevation with a single door, provided with a door opening and closing device of my invention, shown in closed position; Fig. 2 illustrates a portion of a freight car in side elevation with a double door provided with a door opening and closing device of my invention, both 80 doors being shown in closed positions in full lines and in slightly open positions in dotted lines; Fig. 3 is a detail view on a larger scale of the lower portions of the two doors in conjunction with a central stop that defines the fixed meeting plane of the opposed 85 edges of the doors; Fig. 4 is a sectional view on line 4-4 of Fig. 3; Fig. 5 is a sectional view on line 5-5 of Fig. 2; Fig. 6 is a view on a larger scale illustrating the door opening and closing mechanism of Fig. 1; Fig. 7 is a perspective view illustrating the door moving lever in dotted lines and the co-operating block in full lines; Fig. 8 is a sectional view on line 8-8 of Fig. 6; Fig. 9 is 90 a sectional view on line 9-9 of Fig. 6; and Fig. 10 is a sectional view on line 10-10 of Fig. 6.

Like parts are indicated by similar characters of reference throughout the different 100 figures.

The embodiment of the invention illustrated in Figs. 1, 6, 8, 9 and 10 will be first described, Fig. 7 being also referred to as the structure there illustrated is common to 105 both embodiments of the invention.

The single door 1 is mounted to move bodily substantially in its own plane, this door having rollers 2 mounted at its top side that roll upon the door supporting track 3 which, 110 as illustrated, is mounted upon the side of a freight car 4. When the door is in posi-

tion to close the door opening in the side of the car, one upright meeting edge thereof engages a face of the upright angle rail 5. This angle rail carries ears 6 and 7 which 5 overlie the outer face of the door to hold it close to the side of the car. The door opening lever 8 is preferably mounted apart from the door and upon one side thereof, this lever being desirably pivoted at its upper end to the ears 6. The block 9 that cooperates with the lever is consequently mounted upon the door. This block is formed with a channel 10 that receives the lever, this channel being so shaped and disposed as to contain the lever in the various positions to which the lever is swung in moving the door and to have one side 11 thereof engaged by the lever therein when the lever is moved in a door opening direction and the other side 12 engaged by the lever when the lever is moved in a door closing direction.

In the preferred embodiment of the invention the channel is obliquely disposed to 25 reduce the lateral extent of the channel as much as possible to reduce to a minimum the looseness or lost motion of the lever within the channel.

The block is formed with portions 13 and 30 14 which overhang the channel 10 and the lever therein, both overhanging portions serving to maintain the lever and block in assembly when the door is closed and until the door is sufficiently open to permit movement of the lever between the overhanging portions, these overhanging portions having opposing edges that are obliquely arranged and spaced apart sufficiently to permit the lever to be moved through the space between 35 these opposing edges when the lever has been sufficiently swung in a door opening direction to bring it into alignment or registry with the space between said opposing oblique edges of said overhanging portions 40 of the block. Fig. 6 illustrates in dotted lines the position to which the lever may be swung in order that it may be passed into or out of the channel 10 through the space between the opposing oblique edges of the 45 channel overhanging portions 13 and 14.

When the lever is moved out of the channel to become free of the block 9 such block 50 may be employed as a handle further to shift the door and in order that the block 55 may better function as a handle I give it a swinging or hinged connection at 15 with a block supporting iron 16 that is bolted to the door. When the door is in a closed position the lever is overhung by both overhanging parts 13 and 14 of the block to enable the 60 lever to take part in holding the door closed, these overhanging parts 13 and 14 also serving to keep the lever in its own plane in which it may be further held by means of 65 the hook 17 that is provided upon the lever

and the eye 18 passing through the opening 19 in the lever and through which the free end of the hook is also projected. The hook 70 may be provided with an apertured ear 20 and the free end of the hook may also be apertured to enable a sealing wire 21 to be assembled with the hook after the free end of the hook has been passed through the eye 18, the ends of the wire 21 having any usual or suitable car seal applied thereto. 75

The embodiment of the invention illustrated in Figs. 2, 3, 4, and 5 is employed in conjunction with a double door and as many of the features of the invention illustrated in these four figures are similar to features 80 illustrated in the remaining figures, similar parts of both embodiments of the invention are given similar characters of reference.

In the structure of Figs. 2, 3, 4, and 5 the door 1 is similar to the door 1 of the remaining figures and is similarly equipped with the supporting rollers 2 that turn upon the track 3 as the door is moved in its own plane. When the door opening in the side of the freight car 4 is closed the door 1 is 90 brought to its closed position when the rail 1' on the bottom of this door engages the central lug 22. Similarly, the door 23 is brought to its closed position when the rail 23' on the bottom of this door engages said 95 central lug. Fig. 3 illustrates the interrelation of the central lug 22 with the bottom rails 1' and 23' on the bottoms of the doors 1 and 23, the structure here illustrated being well known to those skilled in the art. 100 The upright angular meeting rail 5' is mounted upon the upright door meeting edge of the door 23 and it is upon this meeting rail that the ears 6 and 7, the lever 8, and the eye 18 are carried. The lever 8, in the 105 structure of Fig. 2, has the same interrelation and co-operation with the block 9 as it does in the structure of Fig. 1, and the channel overhanging portions 13 and 14 also serve the same purpose in the structure of Fig. 2 as they do in Fig. 1, which is also 110 true of the hook 17 and eye 18. When the lever is swung to the position shown in dotted lines in Fig. 2 the doors are moved apart or are so relatively moved that the gap 115 between them is about the same as the gap which is effected when the lever is given a similar movement when employed with the structure of Fig. 1.

While I have herein shown and particularly described the preferred embodiment of my invention I do not wish to be limited to the precise details of construction shown as changes may readily be made without departing from the spirit of my invention, 125 but having thus described my invention I claim as new and desire to secure by Letters Patent the following:

1. The combination with a door mounted to move bodily substantially in its plane; of 130

mechanism for forcing the bodily movement of the door comprising one element in the form of a block and another element in the form of a lever engaging the block, one of these elements being carried by the door and the other being mounted apart from the door upon one side thereof, the block being formed with a channel that receives the lever and is oblique to contain the lever in the various positions to which the lever is swung in moving the door and to have one side thereof engaged by the lever therein when the lever is moved in a door opening direction and the opposite side engaged by the lever therein when the lever is moved in a door closing direction, the block being formed to overhang said channel to prevent removal of the lever from the channel when the door is closed and permit removal of the lever when the door is sufficiently opened.

2. The combination with a door mounted to move bodily substantially in its plane; of mechanism for forcing the bodily movement of the door comprising a block swingingly mounted upon the door, to be serviceable as a handle, and a lever engaging the block and mounted apart from the door upon one side thereof, the block being formed with a channel that receives the lever and is oblique to contain the lever in the various positions to which the lever is swung in moving the door and to have one side thereof engaged by the lever therein when the lever is moved in a door opening direction and the opposite side engaged by the lever therein when the lever is moved in a door closing direction, the block being formed to overhang said channel to prevent removal of the lever from the channel when the door is closed and permit removal of the lever when the door is sufficiently opened.

3. The combination with a door mounted to move bodily substantially in its plane; of mechanism for forcing the bodily movement of the door comprising one element in

the form of a block and another element in the form of a lever engaging the block, one of these elements being carried by the door and the other being mounted apart from the door upon one side thereof, the block being formed with a channel that receives the lever and is shaped and disposed to contain the lever in the various positions to which the lever is swung in moving the door and to have one side thereof engaged by the lever therein when the lever is moved in a door opening direction and the opposite side engaged by the lever therein when the lever is moved in a door closing direction, the block being formed to overhang said channel to prevent removal of the lever from the channel when the door is closed and permit removal of the lever when the door is sufficiently opened.

4. The combination with a door mounted to move bodily substantially in its plane; of mechanism for forcing the bodily movement of the door comprising a block swingingly mounted upon the door to be serviceable as a handle and a lever engaging the block and mounted apart from the door upon one side thereof, the block being formed with a channel that receives the lever and is shaped and disposed to contain the lever in the various positions to which the lever is swung in moving the door and to have one side thereof engaged by the lever therein when the lever is moved in a door opening direction and the opposite side engaged by the lever therein when the lever is moved in a door closing direction, the block being formed to overhang said channel to prevent removal of the lever from the channel when the door is closed and permit removal of the lever when the door is sufficiently opened.

In witness whereof, I hereunto subscribe my name this twenty-first day of January A. D., 1921.

HERMAN C. PRIEBE.
